UNITED STATES PATENT OFFICE.

WILLIAM H. BURK, OF TAMPA, FLORIDA.

LOCK.

Application filed July 28, 1921. Serial No. 488,111.

To all whom it may concern:

Be it known that I, WILLIAM H. BURK, a citizen of the United States, residing at Tampa, in the county of Hillsborough and 5 State of Florida, have invented certain new and useful Improvements in Locks, of which the following is a specification, reference being had therein to the accompanying drawing.

10 This invention relates to locks. It is particularly adapted to lock the valves of inner tubes of automobile tires onto the rims of vehicle wheels when the same are in use or when carried as a "spare," so that the unauthorized removal of the tire and tube can be frustrated.

Objects of the invention are to provide a simple device which can be manufactured at a relatively small cost; one which can be 15 attached to valves now in use; one which will be easy to apply; and one which will be positive in its action.

Other objects and advantages will be apparent from the following specification.

20 In order that the invention may be readily comprehended. I have disclosed the same in the accompanying drawings, wherein:

Figure 1 is a view in elevation of the device attached to a wheel;

25 Fig. 2 is a view in vertical cross-section of a valve with which there are associated a sleeve, cap, and locking means comprising an embodiment of the invention;

Fig. 3 is a view in horizontal cross-section on the line 3—3, Fig. 2;

Fig. 4 is a detail view of the sleeve-engaging members of the locking mechanism;

30 Figs. 5 and 6 are views of a modified form of construction, Fig. 6 being a sectional view 40 taken on the line 6—6, Fig. 5; and

Fig. 7 is a view in cross-section on the line 7—7, Fig. 6.

The structure of my invention contemplates a housing-member, a swinging-member therein, means for positioning the swinging-member in relation to a valve-stem and the like, and a locking-device associated therewith and acting on the swinging-member to lock it in position. Herein, I have 45 disclosed two species or embodiments of the invention, both of which include the combination of elements just set forth.

50 Referring to the embodiment shown in Figs. 1 to 4, the reference-character 1 designates a tire-casing mounted on a rim 2 which may be fixed or demountably at-

tached to a felly 3, in the usual manner. The tire-casing has the usual inner tube 4 provided with a valve-stem 5 fixed therein and extending through the rim and felly. 60 The valve-stem is, as usual, threaded throughout its length and is encompassed by a sleeve 6 provided with at least one flattened side 6^a and secured to the rim 2. A jam-nut 7 holds a spreader member 8 and the 65 wall of the inner tube 4 in compressed relation against the head 9 of the valve-stem. A nut 10 is also threaded on the valve-stem and bears against the felly to cover the hole therethrough for the reception of the valve- 70 stem.

Mounted on and fitting over the valve-stem is a housing-member or cap 11 for excluding dust and any foreign matter from 75 entering the valve.

Means are provided for locking the housing-member over the valve-stem and, as herein shown, this comprises a sleeve-engaging member or finger 12, preferably elongated and provided on its inner surface 80 with threads 13. Preferably, I associate with this member a companion sleeve-engaging member or finger 14 and, as here shown, these members 12 and 14 are pivotally connected at 15 for relative movement 85 toward and away from each other and in relation to the sleeve 6 which they are adapted to engage, and are also provided near their upper ends with inwardly projecting jaws or lugs 16 and 17 so that, when the 90 members 12 and 14 are in locked position, an approximate circle is formed, a slight space or gap 18 being left where the ends of the jaws do not meet for the purpose of receiving a rotatable member 19, presently to 95 be described.

Each of the members 12 and 14 has a swinging movement toward and away from each other and toward and away from the sleeve 6 to engage the threads and flattened 100 surfaces thereof, and such relative movement is effected by the following structure:

Located in the upper end of the housing-member 11 is a barrel-element 20 forming a component of a locking-device of suitable 105 construction, but preferably of the pin tumbler type. As here shown this comprises a barrel 21 rotatably mounted within sleeve 20 and provided with a keyhole. Sleeve 20 is provided with openings 23 within which locking pins are disposed, the barrel 21 having corresponding openings adapted to 110

bring the pins into opening position when a key 22 is inserted as shown in Fig. 6. Associated with the barrel 21 is a rotatable member or spreading wedge 19, above-noted, 5 preferably elliptical in shape, which is adapted to register with the wedge-receiving space 18 formed between the converging ends of the stem-engaging members. When in unlocked condition, the spreading-member 10 is adapted to be in a vertical position, as shown in dotted lines in Fig. 2, the upper end being disposed in the gap formed by the non-meeting ends of the lugs. However, when in locked condition, the spreading-member 15 is turned by the action of the key in the lock and the associated barrel and tumblers so that the ends of the spreading-member impinge against and exert pressure on the inwardly-curved sides of the lugs of 20 the sleeve-engaging members until the lower threaded ends thereof are forced against the flattened and threaded surfaces of the sleeve and thus prevent movement of the housing-member in any direction. This locking action 25 holds the valve with its associated housing-member immovable against the rim or felly of the wheel to which it is attached, so that the inner tube cannot be deflated or the tire and tube removed from the rim by 30 unauthorized persons.

Means are also provided for preventing the entrance of any foreign matter into the lock through the keyhole 23 and, as here shown, this comprises a dust-excluding member or cover 24 hinged at 25 to the upper end of the housing member and held in closed position by a spring-member 26 35 or the like.

Operation: The operation of the device 40 will be apparent from the foregoing description, and it will suffice here to state that, in applying the device, the user places the housing cap with its associated sleeve engaging members over the sleeve 6, the 45 screw threads on the members meshing with those on the sleeve, and the cap is rotated until it abuts against the wheel-felly. Then, the user inserts the key in the lock and turns the same so that the tumbler with its associated spreading wedge-member is forced 50 against the circular-shaped edges of the upper part of the stem-engaging members, thereby pressing the lower ends of the members tightly against the sleeve. It will thus 55 be apparent that the housing cannot be removed from the stem so that unauthorized persons will be unable to remove the tire from the rim or wheel.

While I have, in the foregoing, described 60 the preferred construction of my invention; nevertheless, there are certain types of wheels where there is not sufficient space to permit the use of such a device. For the purpose of providing a satisfactory fastening 65 for wheels of this latter construction,

I have devised the locking means shown in Figs. 5 to 7 of the accompanying drawings. As therein revealed, the locking-device consists of a sleeve engaging-member 27 provided with an opening 28 therethrough to 70 receive the sleeve. This sleeve opening is screw-threaded throughout its length in order that it may mesh with the threads on the sleeve.

Means are also provided for housing the 75 lock-member and, as herein shown, this comprises a lock-receiving portion 29 outstanding from the sleeve-engaging portion and provided with locking means of any usual construction, but preferably of the pin tumbler type and including a rotatable barrel 30 with its associated tumblers 31 meshing with grooves in a key 32, as understood. Associated with, and preferably formed as 80 a part of the barrel 30, is a swinging-member 33 adapted to have movement in a passageway 34 formed in the sleeve engaging portion of the lock-member and which impinges against the sleeve 6 when brought 85 into and held in that position by movement 90 of the key 32 and its associated barrel and tumbler-mechanism.

Operation: The operation of this modified form of the device will be understood 95 from the foregoing description; but it may be here stated that, when the user inserts the key in the lock and turns the same until the tumbler with its associated swinging-member is brought into engagement with the flattened side of the sleeve 6, said swinging-member will be held tightly against the 100 sleeve so that unauthorized removal of the tire will be frustrated.

From the foregoing, it will be perceived 105 that I have provided a simple but effective device for locking the valve-stem and its associated housing or dust-cap on the tire, and one which will tend to prevent the unauthorized removal of the tire and inner tube from the wheel. It is to be understood, however, that the embodiments of the invention herein revealed, and the manner of attaching the same, are not the only embodiments and utilizations possible or contemplated by my inventive concept; and 110 even the revealed embodiments are susceptible of a wide range of modification and variation without departing from the salient features and underlying principles of 115 the invention.

What I claim is:

1. A lock for vehicle tires comprising a sleeve secured to a portion of a vehicle wheel and adapted to encompass a valve stem; a valve cap adapted to encompass a portion of the sleeve and stem and inclose them; a lock disposed on the cap; locking members, pivotally connected intermediate their ends, disposed within the cap, said members having at one end a portion adapted to inter- 120 125 130

lock with the sleeve; and a member connecting the lock and locking members whereby actuation of the lock will operate the locking members.

5. 2. A lock for vehicle tires comprising a sleeve secured to a tire rim and encompassing a portion of a valve stem; a cap adapted to be placed over a portion of the stem; means for locking the cap to the sleeve when the cap is placed over a portion of the stem, said locking means including a sleeve-engaging member on the cap; a member for forcing the sleeve-engaging member into engagement with the sleeve; and a portion of the sleeve and engaging-member being threaded to effect a locking of these parts when pressed together.

20 3. A lock for vehicle tires comprising a sleeve secured to a tire rim and encompassing a portion of a valve stem; a cap adapted to be placed over a portion of the stem; means for locking the cap to the sleeve when the cap is placed over a portion of the stem; said locking means including a sleeve-en-

gaging member mounted for movement into and out of engagement with a portion of the sleeve; and means for effecting this movement, said means including a key and lock mechanism comprising a tumbler and cylinder operable by the key.

25 4. A lock for vehicle tires comprising a sleeve secured to a tire rim and encompassing a portion of a valve stem, said sleeve having a threaded and flattened portion on a surface thereof; a cap adapted to be placed over a portion of the valve stem; a sleeve-engaging member mounted for swinging movement into and out of engagement with the sleeve; and a locking member operably connected with the swinging member and cap.

30 35 40 In testimony whereof I affix my signature in presence of two witnesses.

WILLIAM H. BURK.
